[57] CLAIM

The ornamental design for a combined ultraviolet light toothbrush holder stand, therefor, as shown.

DESCRIPTION

FIG. 1 is a top perspective view of a combined ultraviolet light toothbrush holder and stand therefor showing my new design;

FIG. 2 is a right side elevational view thereof;

FIG. 3 is a bottom plan view thereof;

FIG. 4 is a top perspective view of the holder shown separately for clarity of illustration only;

FIG. 5 is a bottom perspective view thereof;

FIG. 6 is a left side elevational view thereof;

FIG. 7 is a right side elevational view thereof;

FIG. 8 is a bottom plan view thereof; and,

FIG. 9 is a bottom perspective view of a second embodiment thereof, shown separately from the stand for clarity of illustration only, the only difference from the first embodiment resides in the adhesive strip.
